UNITED STATES PATENT OFFICE

CURTIS T. CLIFFORD, OF SAN FRANCISCO, CALIFORNIA

PORTABLE FIRE EXTINGUISHER AND SPRAYER

Application filed March 18, 1932. Serial No. 599,707.

My invention relates to portable fire fighting apparatus and sprayers, and my improvements are applicable particularly to the knapsack type of device and to facilitate the carrying and handling of the apparatus.

While not limited to use in fighting forest and brush fires it is particularly applicable thereto, and my improvements enable the user to transport and operate the device with the least fatigue and interference, and therefore to secure the greatest efficiency in his fire fighting efforts.

This class of device is kept ready at hand to be employed on instant call and frequently must be transported by hand or on the back of the operator over considerable distances, often through brush and undergrowth, and during such time it is imperative that it be least obstructive to his efforts and ready at hand for instant use.

I have found that in using apparatus of this class the operator who upon instant call wishes to employ the device may be tall or short, right or left handed; he may employ it in the open but more usually will have to pass through brush and undergrowth while he is transporting it to the place of use, and that projecting parts if fixed with the tank portions not infrequently engage with the brush and tear the device from his hands or back, or throw him to the ground, resulting in injury to the apparatus or person and delay at a critical time.

With these objects in mind I provide a supply tank formed on both sides to fit the operator and adapted to contain a fluid extinguisher or a sprayer medium; a flexible hose connection, a nozzle and a pump for forcing the fluid through the nozzle, fixtures for retaining the parts in compact form until the pump is to be used, and also for carrying the assembled apparatus either by hand or strapped to the shoulders; the assembled parts thus forming an integral structure, light, compact and convenient and most efficient for forest fire fighting and the like, or for general spraying purposes.

By referring to the drawing my invention will be made clear.

Figure 1 is a perspective view of the assembled apparatus.

Figure 2 is a section of Figure 1 on the line II-II thereof.

The tank or container is indicated by the numeral 1a, and this is adapted to contain the liquid or fluid extinguisher or spray to be employed.

At 2 is a suitable form of closure cap to give access to and for filling or cleaning the tank.

At 3 is a bail pivoted at 4, 5, having spring clips 6, 7, adapted to receive and frictionally hold the pump and nozzle portions of the apparatus 15, 16, during transportation and handling and while the pump is not actually being used. These clips automatically release the pump on passing through and engaging brush, their open ends always being to the rear and away from the directions in which the operator moves.

The several positions as 3a and 3b into which the bail 3 may be swung also enable the tank to be filled through the cap 2 with the greatest facility.

At 8, 9, are connections on the upper portion of the tank, and at 10, 11, other connections on the lower portion to which convenient shoulder straps, well known but not shown, may be attached.

Referring to the tank, it will be noticed that its two outer sides are curved to fit the back of the operator as shown at 1a, 1b, respectively, and that in using the apparatus it matters not which way it be picked up; either side will equally well adapt itself to the back of the operator with the maximum of comfort. The bail 3 likewise is adapted to swing from the full line position through a full range to the other side of the tank as shown by dotted lines at 3a, or into the upright position as shown at 3b, in which latter position it may be used as a handle.

A spring device at 12 may be employed to frictionally retain the bail in the position 3b so that it is always ready to be quickly picked up by hand, swung into position on the back and may then freely fall or be forced into position 3a if the side 1a contacts with the back, or into position 3 if the side 1b contacts with the back.

At 13 is a nipple outlet from the tank 1 connected with the hose 14, with the pump and handle portion 15, and nozzle outlet 16, through which the extinguishing fluid is ejected by hand operation.

It will be noticed that with the bail in either position 3 or 3a away from the back of the operator any projecting portion of the nozzle or hose or pump which engages

- 10 with underbrush will automatically pull the nozzle and associated parts out of the spring clips 6, 7, as the operator is proceeding, without throwing him or tearing the apparatus from his shoulders. This is a very important
- 15 improvement in devices of this kind as in forest fire fighting the operator making his way through the forest must not be impeded in his progress, nor must his attention be diverted from making his way with despatch
- 20 and accuracy by having to disentangle himself or the apparatus he is carrying, or having to circumvent brush and undergrowth in order to get his apparatus through.

For the same reason, quickly grasping the apparatus by the bail in the position 3b from where it may be located prior to a call for use, he must not be delayed or have his thoughts diverted by some special requirements in the positioning upon his shoulders

- 30 or back. He must be able to pick it up and throw it on his back, and my device will at such time fall into position with the bail swung clear of his back and with the nozzle in the proper position, whether he be right or
- 35 left handed, and without further effort or thought, and to proceed without portions of the apparatus jabbing him in the ribs or spine, and whether he be tall or short, thin or fat, until he arrives at the point of use
- 40 when it must be instantly available for that purpose.

I claim:

1. A portable fire extinguisher and sprayer comprising a tank having opposite sides each shaped to fit the back of an operator; a flexible hose attached to said tank; force pump means having one end connected to said hose; a bail pivoted to the upper portion of and adapted to swing to either side of said tank; spring clip means fixed to said bail and adapted to frictionally grip said pump means.

- 55 2. A portable fire extinguisher and sprayer comprising a tank having opposite sides each shaped to fit the back of an operator; a flexible hose attached to said tank; force pump means having one end connected to said hose; a bail pivoted to the upper portion of and adapted to swing to either side of said tank; spring clip means fixed to said bail and adapted to frictionally grip said pump means, and other means adapted to detachably hold said bail in a predetermined position.

- 65 3. A portable fire extinguisher and sprayer

comprising a tank having opposite sides each shaped to fit the back of an operator; a flexible hose attached to said tank; force pump means having one end connected to said hose; a bail pivoted to the upper portion of and 70 adapted to swing to either side of said tank; spring clip means fixed to said bail and adapted to frictionally grip said pump means, and a friction engaging device adapted to detachably hold said bail in an upright 75 position.
